TRAP NEST FOR HENS

Otto Strohschneider, Graz, Austria

Application April 4, 1931, Serial No. 527,734, and
in Austria February 13, 1930

4 Claims. (Cl. 119—49)

For determining the laying capacity of hens, so-called trap nests have been employed, that is box-like nests with hinged doors, usually only oscillatable in inward direction, which are either supported in inclined position, the support being removed by a hen entering the nest so that the door drops and confines the hen in the nest, or are made in two parts, the lower part being swung upwards and adapted to drop when a hen enters a nest. The hens which are each provided with a mark, must be freed from the nest and, when liberating the hen, this mark can be noted and in this manner the laying capacity of each hen determined.

5 Trap nests are also known with hinged doors, which are only oscillatable outwards of the free locking position and in which the door is maintained in locked condition by an automatic locking device adapted to be actuated on being 10 touched.

10 The present invention relates to improvements in the latter type of trap nests.

An embodiment of the invention is illustrated by way of example in the accompanying drawing, in which:

25 Fig. 1 shows the trap nest in front elevation with a portion of the door removed.

Fig. 2 is a vertical cross section on line 2—2 of Fig. 1, showing the front portion of the nest.

30 Fig. 3 shows the locking device in inoperative position.

35 On the front wall R of the nest, provided with an aperture, a door T is suspended in the aperture in the wall R by means of an iron band frame S extending along the upper edge of the door and having two arms U downwardly bent at right angles, extending one on each side half way down the side of the door T. In each of the arms U a hole is provided directly 40 below the band S through which a rod D resting in horizontal position in holes in the nest extends. The lower ends of the arms U are oscillatably connected to the sides of the door T by means of screws V. Thus, the door can 45 oscillate around the screws V and the frame can oscillate on the rod D. On each side of the lower end of the door T pins K project laterally, and near the upper end of the front wall R of the nest downwardly extending hooks 50 G are provided one on each side. For setting the nest, the door is swung inwards on the frame S around the rod D and the lower end of the door oscillated around the screws V so that the pins K engage in the hooks G, so that the door assumes the position shown in dotted lines

in Fig. 2. When a hen enters the nest, it must brush against the end of the door and disengage the pins K from the hooks G, so that the door returns into its initial or closed position. In order to prevent the door from swinging beyond its vertical position, stops J are provided on the upper end of the door, which come into contact with the inner side of the front wall R of the nest, the lower end of the door coming into contact with abutments N arranged on each 60 side of the aperture on the front wall R.

65 On the lower end of the door T a snap hook H is mounted in a U-shaped sheet metal casing P provided with lateral flaps L, by means of which the casing is fixed on the door. This 70 hook H slides over and engages a strap E fixed on the wall of the nest at the lower edge of the aperture when the door drops into its closing position. Thus the door is automatically locked in this closed position. For disengaging the 75 snap hook H it is only necessary to depress same. The upper edge of the casing P is bent over to form a hook O, in which the end of the snap hook H extending into the nest can be engaged by depressing the end of the hook H, 80 projecting from the casing, so as to render the snap hook inoperative.

85 The snap hook H is locked in the position shown in Fig. 2 after the hen has entered the nest. If it is desired, after inspection, to allow the hen to leave the nest, the snap hook must be rendered inoperative. For this purpose the wire on which the snap hook is oscillatably mounted is bent to form a rectangular frame B which generally hangs downwards. If, before 90 closing the nest after inspection, this frame is however raised so that it rests on the strap when the door is closed, it supports the snap hook H as shown in Fig. 3 so that it cannot engage the strap E. When the hen leaves the 95 nest, it raises the door T and allows it to drop into its hanging position so that the snap hook can engage the strap E when the door again closes thereby locking the door and the nest with the egg laid by the hen which has just 100 left the nest. The number of the hen can be noted during the inspection and marked on the door of the nest.

105 In order to release the hen from the nest, after the engagement of the snap hook with the strap E, it is merely necessary to press the outer end of the snap hook in downward direction and oscillate the door around the rod D.

What I claim is:

110 1. A trap nest for hens, comprising in com-

bination with the front wall of the nest having an aperture, a door in said aperture to close the nest, a frame extending along the upper edge and having two arms extending half way down 5 the corresponding side of said door, and having holes at the upper end, screws hingedly connecting the lower ends of said arms to the sides of said door, a horizontal rod supported in said front wall extending across said aperture and 10 through the holes in said arms adapted to allow the oscillation of said frame, stops on the inner side of the upper end of said door adapted to bear against the inner side of the upper portion of said wall when said door is in closed position, 15 two abutments on the inner side of said front wall extending into the aperture thereof adapted to limit the oscillation of said door around said screws when said door is in closed position, two pins extending laterally one from each side of 20 the lower end of said door, and hooks on the outer side of said front wall one on each side of the aperture thereof adapted on said door being oscillated outwards around said screws and swung into the nest with said frame to engage 25 said pins and hold said door in the inclined position.

2. A trap nest as specified in claim 1, comprising in combination with the front wall and the door, a casing mounted on the lower end of

the said door, a snap lock oscillatably mounted in said casing, and a strap on said front wall extending beyond the lower edge of said aperture adapted on the closing of said door to engage said hook and lock said door in closed position. 80

3. A trap nest as specified in claim 1, comprising in combination with the front wall and the door, a casing mounted on the lower end of said door, a snap lock oscillatably mounted in said casing, a strap on said front wall extending beyond the lower edge of said aperture adapted on the closing of said door to engage said hook and lock said door in closed position, and a catch hook in said casing adapted to lock said snap hook in inoperative position. 85

4. A trap nest as specified in claim 1, comprising in combination with the front wall and the door, a casing mounted on the lower end of said door, a snap lock oscillatably mounted in said casing, a strap on said front wall extending beyond the lower edge of said aperture adapted on the closing of said door to engage said hook and lock said door in closed position, and a rectangular element serving as pivot for 90 said snap hook adapted to be slipped over said strap and prevent the engagement of said hook. 95
